UNITED STATES PATENT OFFICE.

JOSEPH F. COMEE, OF CHICAGO, ILLINOIS, ASSIGNOR TO CAMEL COMPANY, OF CHICAGO, ILLINOIS, A CORPORATION OF MAINE.

CAR-DOOR.

1,076,484.

Specification of Letters Patent.

Patented Oct. 21, 1913.

Application filed April 23, 1912. Serial No. 692,637.

To all whom it may concern:

Be it known that I, JOSEPH F. COMEE, a citizen of the United States, and a resident of the city of Chicago, county of Cook, and State of Illinois, have invented certain new and useful Improvements in Car-Doors, of which I do declare the following to be a full, clear, and exact description, reference being had to the accompanying drawing, forming part of this specification.

The present invention relates more particularly to the door mechanism of railway freight cars, and the invention consists in the features of novelty hereinafter described, illustrated in the accompanying drawings and particularly pointed out in the claim at the end of this specification.

Figure 1 is a view in elevation showing part of a freight car having my invention applied thereto. Fig. 2 is a view in horizontal section on line 2 of Fig. 1. Fig. 3 is an enlarged detail view in vertical section on line 3 of Fig. 1. Fig. 4 is a view in vertical section of the door on line 4 of Fig. 1. Fig. 5 is an enlarged detail view in vertical section on line 5 of Fig. 1. Fig. 6 is an enlarged detail view in vertical section on line 6 of Fig. 1.

The primary object of my present invention is to provide an improved construction of metal door more especially adapted for closing the side entrances of railway freight cars.

Metal doors for railway freight cars have heretofore been employed, but none of such doors have met the requirements of strength and rigidity as effectively as the door embodying the features characteristic of my present invention. In the construction of railway freight cars it is highly desirable that the door shall occupy as little space in the width of the car as possible, as by reducing the thickness of the door—and particularly its thickness at top and bottom—a greater width in the interior of the car may be obtained, it being understood that the limits of width of a freight car are determined by its outside dimensions.

A further object of my invention is to afford a most effective support for the car door which will protect the top of the door and its supporting track from the weather, and which will prevent moisture getting into the car at the back of the trolley track.

A designates the side wall of a freight car and a denotes the side doorway that is shown as provided with the usual side posts B and B', with a cross lintel C and with a bottom sill D. The lintel C is formed with a recess e in its outer face and within this recess is set the trolley track E, this track being held in place by suitable through bolts F. As shown, the trolley track E is in the shape of a Z-bar, the major portion of which is held within the longitudinal recess e formed in the face of the lintel, this recess serving to protect the trolley track E in great measure from the accumulation of ice, snow and the like, and serving also to prevent any passage of moisture behind the trolley track and thence into the car. The horizontal portion e of the trolley track rests upon the outwardly projecting lower portion c' of the lintel C and is effectively sustained thereby, while the lower depending flange e' of the trolley track is spaced at a distance from the outer face of the lintel, sufficient to admit the upper edge of the door G. Preferably, the depending flange e' of the trolley track is formed with inwardly projecting offsets e² which, as the door approaches the closed position, will engage the outwardly projecting offsets g arranged adjacent the upper edge of the door G and will thus force the door tightly toward the face of the lintel C. The offsets e² and g will be integral with the trolley track and door respectively, and will be formed by "bumping" or offsetting the metal by means of suitable dies. Similarly, adjacent the lower edge of the door G offsets g' will be formed, these offsets being adapted to engage with the inner curved faces of the guide irons H that are bolted to the car body adjacent the lower edge of the door, as clearly shown in Figs. 1 and 6 of the drawings. Hence, it will be seen that as the door is moved to closed position its top and bottom will be forced tightly inward toward the face of the doorway by the engagement of the offsets above mentioned; but as the door is moved toward its open position, these offsets are disengaged and a free sliding of the door is permitted.

To the upper portion of the door G are secured the hangers J that carry at their upper ends the trolley wheels j. The hangers J may be of any suitable construction but, to adapt them to the purposes of my

- present invention, each of the hangers is formed upon its inner face with a recess g' within which will set one of the corrugations adjacent the upper edge of the door.
- 5 My improved door G is preferably formed from sheet steel and in order to give it the requisite rigidity the central portion of the door is formed with a series of spiral or circular corrugations g^3 . I prefer that these 10 corrugations should be of spiral shape, as this shape most effectively strengthens the body of the door. Adjacent the top edge of the door there is formed a rib or corrugation g^4 that extends approximately from 15 side to side of the door and adjacent the bottom edge of the door there is formed a similar corrugation g^5 . Each corner portion of the door G is strengthened by a diagonally disposed corrugation g^6 and each of 20 these corrugations g^6 extends from a point adjacent the central corrugations g^3 to a point adjacent the horizontal corrugations g^4 or g^5 . By this arrangement of corrugations very great strength is given to the 25 door and, inasmuch as the inner portions of the diagonal corrugations g^6 extend within the top and bottom line of the central corrugations g^3 , they most effectively aid in giving rigidity to the upper and lower portions 30 of the door. By forming the central portion of the door with spiral or circular corrugations, and by employing the diagonal corrugations at the upper and lower corners of the door, the same dies can be used for 35 the circular corrugated portion of doors of different dimensions, it being only necessary to vary, for doors of materially different sizes, the dies whereby the diagonal corrugations are made. This I regard as a feature of very material advantage, as a large 40 saving in expense of dies is thereby effected.
- The door G is formed at its left-hand edge with an outwardly turned integral flange g^8 (see Figs. 1, 2 and 5) and in this flange 45 g^8 may be formed an opening g^9 to receive
- the fastening whereby the door is locked, such, for example, as a hasp g^{10} shown in Fig. 1 of the drawings. The flange g^8 also adds materially to the strength of the door. The opposite edge of the door G is formed 50 with an integral, reverted flange g^{11} (see Fig. 2) adapted to close over a weather strip M that is bolted to the side post B'. This weather strip is preferably an angle bar, the free member of which projects rearwardly 55 and is arranged at a sufficient distance from the outer wall of the car to permit it to be freely engaged by the reverted flange g^{11} of the door. The reverted flange g^{11} not only affords an effective guard against the 60 weather, by coöperating with the weather strip M, but this flange g^{11} also serves to strengthen the corresponding edge of the door.
- By my present invention an exceedingly 65 strong and rigid metal door is provided, and this door may be made so thin that it will occupy but little space in the width of the car.
- Having thus described my invention, what 70 I claim as new, and desire to secure by Letters Patent, is:—
- A car door, formed of a single thickness of pressed sheet steel, having a circular central portion formed with parallel curved 75 strengthening corrugations extending from the center of the door outwardly to adjacent the edges thereof and lying in a common plane, and additional corrugations located entirely outside of and away from 80 said circular central portion, said additional corrugations extending approximately from side to side of the door adjacent but spaced from its upper and lower edges and terminating short of the side edges thereof. 85

JOSEPH F. COMEE.
